COLVIN L. JOHNSON, OF ST. LOUIS, MISSOURI, ASSIGNOR TO JOHNSON AUTOMOBILE LOCK CO., OF ST. LOUIS, MISSOURI, A CORPORATION OF MISSOURI

REFRIGERATOR-COIL MOUNTING

Application filed February 17, 1927. Serial No. 168,936.

This invention relates to refrigeration coil mountings for installing the expansion or evaporator coils of a refrigerating apparatus in the ice compartments of refrigerators. It is an object of this invention to provide means for mounting refrigeration coils in ice compartments of varying sizes without having bolts projecting through the walls thereof, and with the minimum of fitting or special equipment for iceboxes of varying sizes and makes. Heretofore when installing a refrigerating apparatus in connection with existing refrigerators it has been necessary to provide a number of stock size of expansion or evaporator coil assemblies for each capacity to fit different sizes of ice compartments of the same capacity and then to individually fit the proper coil in the compartment. It is, therefore, an object of this invention to reduce the number of sizes required to the number of capacities desired and to provide an easily adjustable mounting means for these various sizes capable of mounting a unit of a given capacity in various shapes of refrigerator ice compartments.

Other and further important objects of this invention will be apparent from the disclosures in the drawings and specification. This invention (in a preferred form) is illustrated in the drawings and hereinafter more fully described.

On the drawings:

Figure 1 is a front elevation of a refrigerator with a refrigeration coil mounted in the ice compartment thereof by means of the device of this invention.

Figure 2 is a top plan view of a refrigeration coil mounted in position in an ice compartment with the top removed.

Figure 3 is a section on the line III-III of Figure 2.

Figure 4 is a fragmentary detail section of one of the mounting bars.

Figure 5 is an enlarged end view thereof.

Figure 6 is an enlarged fragmentary section of a modified form of bar.

Figure 7 is an enlarged fragmentary section of another modified form of bar.

Figure 8 is a section through a refrigerator showing a modified form of mounting.

Figure 9 is a section on the line IX-IX of Figure 8.

Figure 10 is an enlarged fragmentary detail section of the mounting of Figures 9 and 10.

As shown on the drawings:

The usual refrigerator or ice box 10 is provided with an ice compartment 11 closed by a door 12, the compartment having a metal lining 13 inside the insulation and box wall construction 14. The expansion tank 15, coils 16 and drawers 17 comprise the refrigeration unit which is to be mounted in the ice compartment and connected to the refrigerating apparatus proper, which is not shown in the drawings.

The structures shown in Figures 1 to 7 contemplate supporting the refrigeration unit 70 from a pair of parallel adjustable bars comprising sleeves 18 having either a pin cap 19 to be forced into the lining 13 as shown in Figures 4 and 5; a milled or roughened cap 20 as shown in Figure 7, or a cup-like rubber cap 21 as shown in Figure 6, the last two frictionally engaging the lining. Each bar comprises a pair of the sleeves 18 spread by means of a long threaded rod 22 with nuts 23 engaging the ends of the sleeves, the threaded rod and nuts acting as a jack to force the caps into holding contact with opposite walls of the ice compartment. The tank 15 is suspended from these bars by means of U bolts 24 passing around the tank and secured to bars 25 which are hung from the bars 18 by the hook bolts 26.

In the use of this form of mounting it will be evident that the sleeves 18 and the threaded rods 22 can be easily assembled within and near the top of the ice compartment and then extended into gripping contact with the compartment wall, whether pins or the other forms of sleeve caps are used as the gripping means. After these bars are mounted, the refrigerating unit can easily be inserted and hung therefrom.

In the modified form of mounting shown in Figures 8 and 10, the expansion tank 15 is suspended from cross bars 27, which may be 100

of the same construction as the bars 25, by means of the U bolts 24 as before, and which may have a number of bolt apertures 28 in each end with notches 29 in the bar between the apertures so that if the bar is too long for the width of the refrigerator compartment a section or two can be broken off the end of the bar to reduce the length thereof. Two of these bars 27 are ordinarily used and are supported against the top of the ice compartment on bars 30 which in turn are supported by lag screws 31. The lag screws 31 are ordinarily mounted in the top of the refrigerator box when the same is built, it being desirable that no bolts project through the top surface of the outer cabinet because such bolts would be so cold the exposed surfaces would condense and freeze moisture from the air at room temperature, thus producing objectionable frosted areas on the surface of the cabinet.

An important feature of this invention resides in the adjustability for height of the expansion tank 15 through the threaded stems 25 of the U bolts 24 and the tank clamping bars 24^a associated therewith. Nuts 24^b on the ends of these stems preferably rest in recesses in the bars 27 thus making it possible to have said bars flush against the top of the refrigerator compartment. To take care of different required heights in the field it is only necessary for the person making the installation to properly position stop nuts 24^c on these stems, cut off the ends of the stems if necessary and then screw the nuts 24^b in position on the upper sides of the bars 27. It will thus be evident that I have provided a construction which meets the contingencies of a variety of installations without the necessity of special tools or fittings.

I am aware that many changes may be made and numerous details of construction may be varied through a wide range without departing from the principles of this invention and I, therefore, do not purpose limiting the patent granted hereon, otherwise than necessitated by the prior art.

I claim as my invention:

1. In combination with the ice compartment of a refrigerator, extensible bars adapted to securely engage the walls of said ice compartment and means adapted to suspend a refrigerating unit from said extensible bars, said means being underslung relative to said bars and being readily removable from said compartment by merely raising same off said bars.

2. In combination with the ice compartment of a refrigerator, extensible means adapted to be forced into engagement with the walls of said ice compartment, a refrigerating unit, and means for suspending and supporting said unit from said extensible means.

3. Supporting means for mounting a re-

frigerator unit in various sizes of ice compartments comprising a pair of extensible bars including aligned members having means on the ends thereof adapted to engage opposite walls of the ice compartment, means adapted to force said aligned members apart to engage the opposite walls of the ice compartment and mounting means for said unit connected to said bars in such a manner as to cause said refrigerator unit to hang from said bars.

4. Mounting means for refrigerating units comprising a plurality of supporting bars, transverse supporting bars adjustably supported thereby and U shaped supporting means adjustably secured to and supported by said transverse bars.

5. Mounting means for refrigerating units comprising a pair of supporting bars, transverse bars supported thereby and adjustable thereon and U bolt clamping and supporting means adjustably mounted on said transverse bars.

6. A mounting device for a refrigerator unit including a cylindrical tank, said mounting device comprising a support and means connected to said support and shaped to receive the tank for directly supporting and positioning the unit, said means being adjustable to accommodate tanks of various diameters.

7. A mounting device for a refrigerator unit comprising a supporting structure formed to be adjustably fitted within and supported from the side walls of any one of a number of different sizes of chambers of a refrigerator in which the refrigerator unit is to be positioned and supporting means adjustable to receive various size units and formed so as to be suspended from said structure after said structure has been secured in place within the chamber.

8. A mounting device for accommodating different sizes of refrigerator units comprising a supporting frame, means for suspending the refrigerator unit from the frame and readily detachable from said frame by lifting same from the frame, and clamping means for securing the unit to said suspending means independently of said frame.

In testimony whereof I have hereunto subscribed my name.

COLVIN L. JOHNSON.
